UNITED STATES PATENT OFFICE.

JAMES F. ROWLEY, OF CHICAGO, ILLINOIS.

ARTIFICIAL FOOT.

SPECIFICATION forming part of Letters Patent No. 759,753, dated May 10, 1904.

Application filed September 14, 1903. Serial No. 173,166. (No model.)

To all whom it may concern:

Be it known that I, JAMES F. ROWLEY, a citizen of the United States of America, and a resident of Chicago, in the county of Cook and 5 State of Illinois, have invented certain new and useful Improvements in Artificial Feet, of which the following is a specification.

The main object of my invention is to provide improved construction and arrangement 10 of the parts of an artificial foot, so that under the weight of the wearer and the movement of the leg, as in the act of walking, the same shall in both appearance and effect closely imitate the natural movements of the human foot. 15 I accomplish this object by the device shown in the accompanying drawings, in which—

Figure 1 is a longitudinal vertical section of an artificial foot constructed according to my invention. Fig. 2 is a transverse section on 20 the line 2 2 of Fig. 1.

In the construction shown the shin part 3 of an artificial leg is provided at its lower end with a base part 4, through which extends a vertically-disposed bolt 5. The upper end of 25 the bolt engages a nut 6, bearing on a dowel 7, which extends across the interior cavity of the shin-section 3. The lower end of the bolt 5 is provided with an eye 8, within which is loosely seated the rear end of a foot-core 9. The 30 eye 8 serves as a fulcrum for the foot-core 9. A cushion 10, of sponge-rubber or other suitable resilient material, is seated in suitable recesses in the base part 4 of the shin-section and in the upper part of the foot-core and 35 serves to yieldingly resist the upward movement of the foot-core 9 about its fulcrum. The cushion 10 is made separate from the filling 13, so as to be readily removed and replaced when weakened or worn from long use.

Extending along and below the foot-core 9 40 is a toe-core 11, which is fulcrumed to the forward end of the foot-core 9 by means of a strap of canvas webbing 12, which is folded as shown and secured to both of said cores. The toe-core 11 is extended a considerable 45 distance both forward and rearward of its fulcrum, and the rear part of said toe-core has secured thereto a strap of canvas webbing 18, which extends upwardly at the sides of the 50 foot-core 9 and over the top of the cushion

10. The cushion 10 thus serves to yieldingly resist the movement of the foot-core about its fulcrum and also to resist the movement of the toe-core about its own fulcrum.

All of the parts below the base 4 of the shin-section are surrounded by a body 13, of sponge-rubber or other suitable material, which is reinforced by strips of canvas 14, 15, 16, and 17, which are suitably arranged to support and strengthen the parts of said 60 sponge-rubber body.

The toe-core 11 does not extend to the forward extremity of the foot-body, thus leaving a portion of the toe part of the foot without a rigid core and providing an additional articulation to the foot.

The operation of the device shown will be understood from the foregoing description. It will be seen that no special attention need be paid by the wearer to the working of the 70 foot, the same being entirely automatic and operated by the movement, as in walking, of the shin part of the leg under the weight of the wearer. It will also be understood that the sponge-rubber structure of the foot, together with the articulations provided, will 75 give an action to the foot which is natural in appearance and results.

It will be understood that numerous details of the construction shown may be altered without departing from the spirit of my invention. I therefore do not confine myself to such details except as hereinafter limited in the claims.

What I claim as my invention, and desire 85 to secure by Letters Patent, is—

1. An artificial foot, comprising a foot-core; a toe-core disposed along said foot-core, being fulcrumed near the forward end of same, and extending a considerable distance forward and 90 rearward from said fulcrum; yielding means connecting the rear end of the toe-core with the foot-core; and a body of resilient material surrounding said cores, substantially as described.

2. An artificial foot, comprising a shin member; a foot-core fulcrumed to the shin member; means yieldingly resisting the movement of the foot-core on its fulcrum; a toe-core fulcrumed to said foot-core; and means yield- 100

ingly resisting the movement of said toe-core on its fulcrum, substantially as described.

3. An artificial foot, comprising a foot-core; a toe-core disposed along and below said foot-core, being fulcrumed near the forward end of same, and extending a considerable distance forward and rearward from said fulcrum; a cushion of yielding material seated on the upper side of said foot-core and a strap connecting said toe-core with said cushion and adapted to yieldingly resist the movement of the toe-core on its fulcrum, substantially as described.

4. In a device of the class described, the combination of a shin member; a foot-core fulcrumed near its rear end to said shin member; a resilient cushion interposed between the forward part of said foot-core and said shin member; a toe-core fulcrumed at the forward end of said foot-core and extending a considerable distance forward and rearward of its

fulcrum; and suitable means connecting said toe-core with said cushion and adapted to yieldingly resist the movement of said toe-core on its fulcrum, substantially as described.

5. An artificial foot; comprising a shin member; a foot-core fulcrumed to the shin member; means yieldingly resisting the movement of the foot-core on its fulcrum; a toe-core fulcrumed at the forward end of said foot-core and extending a considerable distance forward and rearward of its fulcrum; and means yieldingly resisting the movement of said toe-core on its fulcrum, substantially as described.

Signed at Chicago this 8th day of September, 1903.

JAMES F. ROWLEY.
